C. COOMER

TOOL

Filed Feb. 13, 1926

UNITED STATES PATENT OFFICE.

CLAUDE COOMER, OF BILLINGS, MONTANA.

TOOL.

Application filed February 13, 1926. Serial No. 88,072.

The object is the provision of a tool in the nature of a band wrench which is especially adaptable for use in removing the clamping rings for automobile headlight lenses, jar covers and the like, and which is adjustable and of a construction whereby a positive grip between the tool and the article engaged thereby is insured.

To the attainment of the foregoing the invention consists in the improvement as hereinafter described and definitely claimed.

In the drawings:—

Figure 1 is a perspective view illustrating the active position of the improvement.

Figure 2 is a perspective view of one end of the improvement.

Figure 3 is a similar view of the other end of the improvement.

The body member of my improvement comprises a band 1 of any suitable tough flexible material which is woven to provide a roughened active face. Riveted or otherwise secured on the outer face at one end of the band there is a plate 2 whose outer end 25 is bifurcated and the arms thus provided are rounded to provide eyes 3 between which there is received and pivoted, as at 4, one end of a lever 5. Pivoted to the lever, at a suitable distance from the pivot 40 there is the bifurcated end 6 of a curved arm 7 that is formed with a laterally extending end 8. The member 7 is thus substantially T-shaped.

Riveted or otherwise secured on the outer face of a second end of the band 1 there is a metal plate 9. The sides of this plate 9 are slotted inwardly and longitudinally at

spaced intervals 9', and metal bounded by the slits is bent to provide pairs of oppositely arranged substantially U-shaped jaws 10. 40

As disclosed by Figure 1 of the drawings the band 1 is arranged around the clamping rim of an automobile headlight lens, and the lever 5 is swung to permit of the lateral head 8 of the T-shaped member 7 being 45 received in any of the aligning pairs of jaws 10, the shank 7 being arranged between said jaws. A pull on the lever will force the ends of the split band toward each other, thus tightly compressing the band around 50 the rim, and a further movement of the lever in the same direction will cause the tool to turn the rim and remove the same from the headlamp. It is obvious that the tool may be successfully employed in applying or removing other devices from their supports, such for instance, as jar covers and the like. 55

Having described the invention I claim:—

A band tool, comprising a split band of woven material, a plate fixed on one end of the band, a lever pivoted to the plate, a T-shaped element having a bifurcated shank which is pivoted to the lever, a plate fixed on the second end of the band and having inwardly directed and longitudinal slits disposed opposite each other and the metal bounded thereby being bent to provide opposite pairs of U-shaped jaws for the reception of the head of the T-shaped element 65 therein and the shank of the said element 70 therebetween.

In testimony whereof I affix my signature.

CLAUDE COOMER.
